SPEED CONTROL FOR ENGINES.

1,194,479.

Specification of Letters Patent. Patented Aug. 15, 1916.

Application filed May 27, 1915. Serial No. 30,842.

To all whom it may concern:

Be it known that we, HARRY C. CLAY and ALBERT T. CLAY, citizens of the United States, residing at Columbus, in the county of Bartholomew and State of Indiana, have invented certain new and useful Improvements in Speed Controls for Engines, of which the following is a specification.

This invention relates to speed controlling devices for steam or internal combustion engines, and is designed more particularly for application to and use in connection with engines of that type wherein the engine shaft is connected by a clutch to a transmission or similar shaft, such engines being commonly employed on automobiles, motor vehicles, tractors, and the like.

Our present improvement has, furthermore, been designed principally for application to governor controlled engines such, for instance, as internal combustion engines extensively used on tractors. The method heretofore employed for changing the speed of a gas tractor has been to change the adjustment of the governor by means of a sector located in the vicinity of the steering wheel.

One of the main objects of the present invention is to provide a mechanism whereby the speed of the engine can be changed by the same lever which operates the transmission clutch, so that when the clutch is engaged the governor will be adjusted so that the speed of the engine will be held normal for doing work, and when the clutch is disengaged, the speed of the engine will be reduced.

A further object of the invention is to save fuel and wear on the engine when running idle.

The above stated objects of the invention are preferably accomplished through a governor adjusting or controlling mechanism, in turn actuated in one direction by a clutch lever and in the reverse direction by a spring, but the broad principle of the invention is applicable to throttle-valve control of engines having no governor, or it may be embodied in a mechanism that is employed with, but is independent of, the governor.

One practical and working embodiment of our invention as applied to a governor controlled internal combustion engine is illus-

trated in the accompanying drawings, in which—

Figure 1 is a plan view showing the clutch disengaged and the governor control set for minimum speed. Fig. 2 is a plan view of a portion of Fig. 1, showing the clutch engaged and the governor control set for maximum speed. Fig. 3 is a side elevation illustrating in full lines the positions of the clutch and governor control shown in Fig. 1, and in dotted lines the position of the same parts as shown in Fig. 2. Fig. 4 is an enlarged fragmentary detail view of the clutch lever and its associated parts shown at the extreme left of Figs. 1 and 2. Fig. 5 is an enlarged detail view of a portion of the governor control mechanism shown in Fig. 3.

Referring to the drawings, 10 designates as an entirety a four cylinder internal combustion engine of a type extensively used on gas tractors.

11 designates the engine shaft, and 12 and 13 the relatively movable parts of the usual transmission clutch by which the engine shaft 11 is connected to and disconnected from the transmission shaft 14.

15 designates the clutch-operating lever fulcrumed on a suitable bracket 16 and at its lower end connected by a link 17 to the outer end of a clutch-engaging lever 18 that is suitably fulcrumed at 19 on a fixed frame piece (not shown).

20 designates the fuel supply pipe of the engine in which is pivoted the throttle valve 21 on the spindle of which is an arm 22 that is connected by a link 23 to one end of a 90 governor-actuated lever 24, said lever being fulcrumed at 25 in a manner more particularly described later, and at its other end being suitably articulated to the lower end of the sleeve 26 of an ordinary centrifugal 95 governor 27.

Referring now to those features wherein our present invention more particularly resides, 28 designates an arm pivotally mounted by a pin 29 on the bracket 16, said arm 28 having a tail-piece 30 that is adapted to swing across the path of movement of the clutch-lever 15, said tail-piece 30 being normally held against the lower or inner edge of the clutch lever 15 by a spring herein-after described. Pivoted to the arm 28 is a

clevis 31 through which extends the threaded end of a connecting rod or link 32, the other end of which is connected to the lower end of a bell crank lever 33, this latter being pivoted at its elbow as shown at 34 to a bracket 35 secured to one of the cylinder jackets or any suitable frame member of the engine. The rod 32 is conveniently and adjustably connected to the clevis 21 by 10 suitable nuts 36 and 37. To the short arm of the bell crank lever 33 is fulcrumed the governor-actuated lever 24 at the point 25, before referred to. To the lower end of the bell crank lever 33 or to the end of the rod 15 32 connected thereto is secured one end of a tension spring 38, the other end of which is anchored at 39 to the crank case or any other suitable frame member of the engine. 20 40 designates a fixed stop on the bracket 16 that is designed to coöperate with an adjustable contact screw 41 mounted in the free end of the arm 28 so as to limit the extent of swinging movement of said arm 28 under the impulse of spring 38. 25 The operation and advantages of the described mechanism will be readily apparent. Assuming that the clutch is engaged and the clutch lever 15 is in its forward position, as indicated by dotted lines in Fig. 3, and the 30 engine is running at normal working speed, when the engine is disconnected from the work by shifting the clutch lever 15 to the full line position (Figs. 1 and 3), the lever 15 through engagement with the tail-piece 30 35 of the pivoted arm 28 swings the latter outwardly and thus through the clevis 31, rod 32 and bell crank lever 33, shifts the fulcrum 25 of the governor-actuated lever 24 upwardly to the full line position shown in 40 Figs. 3 and 5, thereby effecting a movement of the throttle valve 21 in a closing direction and instantly adjusting the governor control to the free running condition of the engine. When the reverse operation takes 45 place and the clutch is thrown into engagement by shifting the lever 15 to its forward position as shown in Fig. 2 and by dotted lines in Fig. 3, spring 38 acts to draw the several parts of the governor control mechanism in the reverse direction until the contact screw 41 strikes the fixed stop 40. This shifts the fulcrum 25 of the governor-actuated lever 24 downwardly, thereby instantly effecting a movement of the throttle valve 50 21 in an opening direction. By the time the lever 15 has been thrown forward to such a point as will permit the movement of arm 28 to be arrested by the stop 40, the clutch is not engaged, which allows the engine to 55 reach full speed before the clutch is applied. This mechanism allows the clutch lever 15 to move in clutch-engaging direction the required amount to engage the clutch without any interference, and should this movement 60 of the lever 15 vary, it does not at all affect 65

the adjustment of the governor control mechanism. Another advantageous feature is found in the fact that the clutch lever 15 can move in clutch-disengaging direction far enough to partly pass the tail-piece 30 70 of the swinging arm 28 after the required movement of said swinging arm is accomplished. This holds the swinging arm in position while this extra movement of the clutch lever 15 is going on. Thus, no accurate adjustment of clutch lever 15 is required to secure the accurate adjustment of the swinging arm 28, which is very important. By means of this device the engine is controlled by the governor at both 75 its normal working speed and its reduced idle running speed. The nuts 36 and 37 are for the purpose of adjusting the throttle valve for the slow or idle running speed by adjusting the length of the connecting 80 link 32, which adjustment should be made first. The screw 41 is for the purpose of adjusting the throttle valve for the fast or working speed.

While we have shown and described our 90 improvements as applied to a governor controlled engine, it will be manifest that if the governor were omitted or were independent of the described mechanism for controlling the throttle valve by the movement of the clutch lever, said mechanism would still operate in the manner described to instantly throttle the engine when the clutch is disengaged and thus prevent racing of the latter, and to automatically open up 10 the throttle just prior to the connecting up of the engine to the transmission shaft. Hence, our present improvements in the broader aspect of the invention are not confined to engines having a governor controlled throttle valve.

The invention is especially valuable in elevating grader work and similar situations where much starting and stopping is required and it is also useful in general traction work.

We claim:

1. The combination of an engine, a transmission clutch, a clutch-actuating lever and connections therefrom to said clutch, a governor and connections therefrom to the throttle valve of the engine, a spring, and means actuated in one direction by said lever and in the reverse direction by said spring for varying the adjustment of said governor-actuated connections to the throttle-valve.

2. The combination of an engine, a transmission clutch, a clutch-actuating lever and connections therefrom to said clutch, a governor and connections therefrom to the throttle valve of the engine, means actuated by said lever when thrown to clutch-disengaging position for shifting said governor-actuated connections in a direction to effect 130

a movement of said throttle valve in a closing direction, and a spring normally tending to shift said governor-actuated connections in the reverse direction to effect a movement of said throttle valve in an opening direction.

3. The combination of an engine, a transmission clutch, a clutch-actuating lever and connections therefrom to said clutch, a governor and connections, including a lever, therefrom to the throttle valve of the engine, a spring, and means actuated in one direction by said clutch lever for shifting the fulcrum of said governor-actuated lever in one direction and actuated in the reverse direction by said spring for shifting the fulcrum of said governor-actuated lever in the opposite direction.

4. The combination of an engine, a transmission clutch, a clutch-actuating lever and connections therefrom to said clutch, a governor and connections, including a lever, therefrom to the throttle valve of the engine, means actuated by said clutch lever when thrown to clutch-disengaging position for shifting the fulcrum of said governor-actuated lever in a direction to effect a movement of said throttle valve in a closing direction, and a spring normally tending to shift the fulcrum of said governor-actuated lever in the reverse direction to effect a movement of said throttle valve in an opening direction.

5. The combination of an engine, a transmission clutch, a clutch-actuating lever and connections therefrom to said clutch, a governor and connections therefrom to the throttle valve of the engine, a spring, means actuated in one direction by said lever and in the reverse direction by said spring for varying the adjustment of said governor-actuated connections to the throttle valve, and an adjustable stop device for controlling the extent of spring-actuated movement of said adjustment-varying means.

6. The combination of an engine, a transmission clutch, a clutch-actuating lever and connections therefrom to said clutch, a governor and connections, including a lever, therefrom to the throttle valve of the engine, a spring, means actuated in one direction by said clutch lever for shifting the fulcrum of said governor-actuated lever in one direction and actuated in the reverse direction by said spring for shifting the fulcrum of said governor-actuated lever in the opposite direction, and an adjustable stop device for controlling the extent of spring-actuated movement of said fulcrum shifting means.

60 7. The combination of an engine, a transmission clutch, a clutch-actuating lever and connections therefrom to said clutch, a governor and connections therefrom to the throttle valve of the engine, and means actuated by said lever upon moving the same to

engage the clutch for adjusting said governor-actuated connection to move the throttle valve in an opening direction prior to engagement of the clutch.

8. The combination of an engine, a transmission clutch, a clutch-actuating lever and connections therefrom to said clutch, a governor and connections therefrom to the throttle valve of the engine, and means controlled upon movement of said lever to clutch-engaging position for effecting movement of said governor-actuated connections so as to move the throttle valve in an opening direction prior to engagement of the clutch.

9. The combination of an engine, a transmission clutch, a clutch-actuating lever and connections therefrom to said clutch, a governor, means operable between the governor and throttle valve of the engine for controlling the engine at either working or idle-running speeds, and means co-operable between the clutch lever and said throttle-controlling means for so operating the latter that upon moving the lever to engage the clutch, the said throttle-controlling means will be moved to working-speed position prior to engagement of the clutch.

10. The combination of an engine, a governor, control connections between the governor and engine adapted to be held in positions to maintain the engine either at working or idle-running speeds, a transmission clutch, a clutch-actuating lever and connections therefrom to the clutch, and means actuated by said lever for so operating the said control connections that in moving the lever to engage the clutch the said connections will be adjusted by said means from idle-running position to working position prior to engagement of the clutch.

11. The combination of an engine, a governor and connections therefrom to the throttle valve of the engine, means for adjusting said connections so that the governor will control the throttle valve in either a predetermined working or an idle-running speed, a transmission clutch, and means for simultaneously operating the clutch and said adjusting means to adjust said connections to working speed position prior to the operation of engaging the clutch.

12. The combination of an engine, a transmission clutch, a clutch-actuating lever and connections therefrom to the clutch, a governor and connections, including a lever therefrom to the throttle valve of the engine, and means actuated by said clutch lever for shifting the fulcrum of said governor-actuated lever.

13. The combination of an engine, a transmission clutch, a clutch-actuating lever and connections therefrom to the clutch, a governor and connections therefrom to the throttle valve of the engine, a lever arranged to be actuated by the clutch-actuat-

ing lever, and connections between the second named lever and the throttle-actuating connections for shifting the latter by throwing the clutch-actuating lever into and out of clutch-engaging position.

14. In a speed control for engines, the combination of an engine, a transmission clutch, a clutch-actuating lever and connections therefrom to the clutch, means for adjusting the throttle valve of the engine whereby to operate the same at any of a plurality of predetermined different speeds, and means actuated upon movement of said clutch-actuating lever from clutch-disengaged to clutch-engaged position, for adjusting said throttle-adjusting means to effect prior to engaging the clutch, a predetermined speed higher than that at which the engine is running.
15. In a speed control for engines, the combination of an engine, a transmission

clutch, a clutch-actuating lever and connections therefrom to the clutch, a throttle-adjusting lever and connections therefrom to the throttle valve of the engine, the clutch lever being coöperable with the throttle adjusting lever for imparting movement to the latter in a throttle-closing direction when the clutch lever is moved to disengaging position, means for imparting movement to the throttle-adjusting lever in a reverse direction when the clutch lever is moved to clutch-engaging position, and an adjustable stop for limiting movement of the throttle-adjusting lever in this latter direction while permitting the movement of the clutch lever to be continued to effect final engagement of the clutch after the said throttle adjusting lever has been stopped.

HARRY C. CLAY.
